UNITED STATES PATENT OFFICE.

ROBERT G. GRISWOLD, OF WESTFIELD, NEW JERSEY, ASSIGNOR TO DOHERTY RESEARCH COMPANY, OF NEW YORK, N. Y., A CORPORATION OF DELAWARE.

METHOD OF DISTILLING COAL.

Application filed April 29, 1922. Serial No. 557,464.

This invention relates to a method of distilling coal and more particularly to a method whereby a high sulphur coal or a coal of inferior grade may be utilized to produce a coke suitable for metallurgical purposes; and also whereby a gas may be obtained which is sufficiently low in sulphur to be suitable for heating and other commercial purposes, and which is below the maximum sulphur content of gas as prescribed by law.

Heretofore high sulphur coals or coals of inferior grade have not been utilized for the production of metallurgical coke for the reason that no economical commercial process has been known by which the excessive sulphur present in the coal could be removed. In the production of gas from such coals it was observed and shown by experiment that in the distillation of coal to produce a coke therefrom approximately 60% of the sulphur content remained in the coke after distillation and 40% of the sulphur content was found to be present in the gas distilled therefrom. An analysis of the sulphur compounds in the gas produced in this way showed that approximately 95% of the sulphur content was present in the form of hydrogen sulphide, and the remainder of the sulphur was present as carbon disulphid and other sulphur compounds such as the thiophenes. Hereafter the latter sulphur compounds will be referred to merely as carbon-sulphur compounds.

Many attempts have been made to develop a practical commercial method of reducing the sulphur content of the coke, as for instance, by passing nitrogen, carbon dioxide and other inert gases therethrough at a high temperature. It has been shown that although the sulphur content is substantially decreased by this means, the high cost of heating the coke and the cost of production of the gas to be employed, has rendered the processes substantially prohibitive. The use of superheated steam has also been experimented with to reduce the sulphur content of the coke, and although a substantial reduction is accomplished by this means, the high temperature which is necessary for the sulphur removal results in a number of the side reactions taking place, such as the water gas reaction, which are undesirable in the coke purification process.

According to the process which I have de-

veloped I propose to distil a high sulphur coal at suitable temperatures and pressures and with the appropriate time interval for distillation to produce a hard coke which when the sulphur content of the same is reduced to the maximum desired value, will be suitable for metallurgical purposes. This I propose to accomplish by purifying the gas distilled from the coal to remove hydrogen sulphide therefrom in the ordinary oxide purifiers and passing the purified gas through the bed of incandescent fuel. The partially purified gas will still contain an objectionable amount of carbon-sulphur compounds which are not removed by the oxide purifiers, and which will be decomposed by passing the gas through the coke chambers in which the distillation of the coal is taking place. In passing the gas through the coke the sulphur content of the coke will also be reduced substantially in accordance with the distribution ratio of the sulphur between coke and gas, as set forth above. The gas after a second purification by passage through oxide purifiers may be returned repeatedly through the coke until the sulphur content thereof has been reduced to the maximum allowable limit. With some coals of fairly low sulphur content a single distillation and purification of gas with a return only of a portion of the gas so distilled through the coke bed will be sufficient to render the sulphur content of both the coke and the gas below the maximum allowable limits.

It is the primary object of the present invention to provide a method whereby high sulphur coals or inferior coals which have heretofore been useless for metallurgical coke production, may be utilized to produce a hard metallurgical coke whose sulphur content is within the maximum allowable limits.

Another object of the invention is to provide a process whereby a gas of the required standard of purity may be economically produced from a high sulphur or inferior grade of coal.

A further object of the invention is to provide a process in which the Doherty shaft furnace may be utilized for the economical production of gas and simultaneous production of a valuable high grade metallurgical coke.

With these and other objects in view the invention consists in the method of making gas and coke hereinafter described and defined in the claims.

5 The various features of the invention are illustrated in the accompanying drawings in which the preferred method of distilling coal may be carried out.

Fig. 1 is a diagrammatical view of the 10 apparatus commonly called the Doherty shaft furnace.

Fig. 2 is a plan view of a shaft coal distilling furnace showing the arrangement of the heat regenerators and connections for 15 the supply of air by a blower and the withdrawal of gas; and

Fig. 3 represents a side elevation partly 20 in section of the shaft furnace, showing a portion of the heat regenerators connected therewith.

In the operation of the apparatus air may be supplied by a blower 10 through pipe 12 either to the bottom of a regenerator tower 16 through pipe 14 as shown in Fig. 1, or 25 to the top of the regenerator through a pipe 18. From thence it passes into the main chamber 17 of the regenerator system, which is filled with checker brick. In the passage through the regenerator the air becomes 30 heated to a high temperature and then passes upwardly through a regenerator tower 20 from which it is led to the middle or lower portion of a shaft furnace 22 through a pipe 24. The fuel which is supplied to the shaft 35 furnace, generally a high sulphur coal, passes downwardly through the furnace and flows over a supporting member 26, near the lower end of the furnace. The fuel gradually works downwardly and is discharged into 40 a hopper 28, having a discharge door 30 at the lower end thereof. Coal mixed with coke is supplied to the apparatus through a hopper 32 leading into the top portion of the shaft furnace and is gradually heated in 45 its passage through the furnace as it progresses toward a heat zone in the middle or lower portion of the furnace. The air from the blower 10 passes through the fuel bed in the zone adjacent to the inlet pipe or nozzle 50 24 and the waste gases leave the furnace through an opening 34 similar to 24 and pass into a regenerator tower 36 similar to tower 20. From the regenerator 36 the waste 55 gases pass through the heat regenerators 37 and 38 similar to regenerators 17 and 16 respectively previously described, the complete arrangement being clearly shown in Fig. 2. The waste gases after passing through the 60 regenerator 38 are discharged into the atmosphere through a pipe 40, having a valve 42 therein. In the passage of the air through the fuel bed the ordinary reaction with the carbon takes place in which carbon dioxide is first formed which is then reduced to carbon monoxide by the incandescent carbon

through which it passes. In order that this carbon monoxide may be completely burned to carbon dioxide before it is discharged into the air, and thus further heat the outlet side of the regenerator, a by-pass 44 leading from the regenerator tower 20 to the tower 36 as shown in Fig. 2 is employed. A secondary combustion takes place in regenerators 36, 37 and 38 by which heat is liberated which further assists in the heating of the 70 regenerator system. By this blowing operation a hot zone in the coke or fuel is formed adjacent the nozzles 24 and 34 which has a temperature in the neighborhood of 2500° F., and is suitable for carrying on the water gas 80 reaction. At this point of the process the air passing through the regenerators to the shaft furnace is cut off and steam is passed through the fuel bed in order to generate water gas. This steam is obtained by passage of water through a pipe 46 into a spray nozzle 48 located below the supporting member 26 in the shaft furnace. The water sprayed into the fuel bed through the nozzle 48 serves a double purpose e. g. it quenches the coke in the bottom of the shaft and the steam generated by the quenching action acts as a medium whereby the heat recovered from the coke is returned to the hot zone of the fuel column and the steam then decomposed into water gas. The water is vaporized and superheated by passage in contact with the hot coke at the bottom of the furnace and passes upwardly through the fuel bed into contact with the heated zone in which the water gas reaction will take place in the well known manner producing hydrogen and carbon monoxide. The main body of steam for the water gas reaction is obtained by introducing water through a pipe 50 at the top of the regenerator 38 directly into contact with the preheated checker brick and then superheating the steam produced by passing it through the regenerators 37 and 36. This steam enters the hot zone 90 through the nozzle 34 and then passes upwardly through the fuel bed together with the steam and gas passing upwardly from the bottom of the furnace. The hot gas passing upwardly from the hot zone acts to distil off the volatile portion of the coal and this gas mixture leaves the top of the furnace through a pipe 52 and passes to a washer cooler 54. The washer cooler 54 serves to remove tar and ammonia from the 100 gas and also to reduce the temperature thereof. From the washer cooler the gas passes through pipe 56 having a valve 57 into an ammonia scrubber 58 in which substantially the last traces of ammonia are removed from the gas in the well known manner. From the ammonia scrubber the gas passes through pipe 60 into the ordinary oxide purifiers 62 which serve to remove hydrogen sulphide 110 from the gas but do not remove carbon- 120

125

sulphur compounds. From the purifiers the gases are led through a pipe 64 into a gas holder 66 which may be of any desired capacity. After the completion of the water 5 gas making operation, the blowing operation is repeated but the gases are circulated in a direction the reverse of the preceding blowing operation. For example air from blower 10 passes through a pipe 67 into regenerator 10 38 then through regenerators 37 and 36 to the furnace. The exhaust gases are burned in regenerator 20 pass through regenerators 17 and 16 to an outlet 69 having a valve 71. The water for making steam for the gas 15 making operation is then admitted through a pipe 80 at the top of the regenerator 16. Coke is mixed with the fuel charged into the furnace only in sufficient quantity to maintain the column of fuel in the shaft in 20 a free and open condition so that the blast air and hot gas currents may easily penetrate to all portions of the charge. The shaft furnace shown in Fig. 1 is so operated that the air for supporting combustion 25 is restricted during its passage through the fuel column to a comparatively narrow zone lying between the nostrils 24 and 34 and it is only in this limited zone that fuel is consumed and temperatures are sufficiently high to support the water gas reaction 30 and to secure a complete decomposition of the carbon-sulfur compounds in the purifying gas circuit. Moreover it is in this limited high temperature zone that the coke 35 products of carbonization can be freed from sulfur impurities by the purifying gases. In the comparatively large section of the furnace above the nostrils 24 and 34 the mixture of high sulfur coal and coke is 40 gradually heated and the coal is carbonized by heat carried by a current of gas generated in the restricted hot zone. The coke produced in this carbonizing zone is very hard and dense because of the fact that it 45 is formed slowly at a comparatively low temperature and because the coal in the lower portion of the carbonizing zone is subjected to the pressure of a great weight of fuel above it during the critical period 50 when it is undergoing a final transformation.

In order to complete the purification of the gas and also to reduce the sulphur content of the coke resulting from the distillation of the high sulphur coals, during the gas making operation, the gas may be returned from the gas holder through a pipe 68 through a booster or gas pump 70 into a pipe 72 from which the gas may be passed either directly into the lower portion of the shaft furnace through a pipe 74 having a valve 76 therein, or it may be passed through a pipe 78, having a valve 81, into the upper portion of the regenerator 16 through which the air during the preceding operation was

preheated. The choice of the point at which to pass the gas freed of hydrogen sulphide depends upon the temperature and equilibrium conditions of the apparatus, and the proper pipe through which to pass the 70 gas during the operation will be apparent to an operator familiar with the gas making process. If the gas is passed through pipe 78 into the top of the regenerator 16, water may be passed through a pipe 80 having valve 82 and spray head 84, into the gas and the gas and water will then pass together through the checker brick in the regenerator. The steam produced and superheated 75 in the regenerator passes together with the preheated gas from the regenerator into the heated zone of the fuel bed and serves to assist in removing sulphur from the coke or fuel bed. The sulphur compounds present in the partially purified gas which is returned are broken down, forming approximately 95% of hydrogen sulphide and 5% of other sulphur compounds. If the partially purified gas is introduced through pipe 74 to the lower portion of the fuel bed 80 below the support 26, it passes upwardly through the column of fuel together with steam formed through the injection of water through pipe 48, and removes, as explained above, sulphur from the coke or fuel bed, substantially in accordance with the distribution ratio of sulphur between the coke and gas heretofore explained and the sulphur compounds in the gas are decomposed to form mainly hydrogen sulphide as 85 heretofore explained. If desired part of the purified gas may be introduced into the furnace through the pipe 74 and the other part of the gas introduced through the pipe 78. The gas which passes out of the shaft furnace through the pipe 52 is again washed 90 and scrubbed in the coolers and scrubbers, and finally passes into the oxide purifiers 62 which serve to remove the hydrogen sulphide accumulated in the gas through decomposition of the sulphur compounds and through the removal of the sulphur from the coke. 95

The gas after being purified may be recirculated if desired to further reduce the sulphur content of the coke in the shaft furnace, or it may be retained in the gas holder 66, if the sulphur content of the gas has been reduced to or below the legal standards 100 and distributed to consumers through a pipe 86 or utilized in any manner desired. 105

In the preferred operation of the apparatus the volume of purified gas which is returned to the furnace is such that when this gas has been passed through the hot fuel bed and mixed with new gas being made, the sulphur contents of the gas mixture and the coke will be below the maximum sulphur content permissible. In this way the sulphur content of all of the gas passing 110 115 120 125 130

through the purifier will be below the maximum sulphur content permissible.

While the operation of the process has been described and explained in connection with a Doherty shaft furnace, its application is by no means limited to this form of apparatus, and may be employed with advantage to other forms of gas producing apparatus.

Having thus described and explained the nature and objects of the invention, what is claimed as new is:

1. The method of utilizing high sulphur coal for the production of metallurgical coke which comprises distilling the coal by direct heat transfer with a hot low B. t. u. gas so as to produce a rich gas having a high sulphur content and coke, burning a portion of the hot coke thus produced and passing the hot gaseous products of the combustion through the remaining coke so as to raise its temperature to incandescence, contacting steam with said incandescent coke to generate the low B. t. u. gas heating medium, purifying the enriched gas by removing hydrogen sulphide therefrom, and returning the purified gas into direct contact with the incandescent coke remaining to decompose the other sulphur compounds remaining in the gas and to reduce the sulphur content of the coke.

2. The method of utilizing high sulphur coal in the production of combustible gas and metallurgical coke which comprises distilling said coal so as to evolve gas and produce coke, burning a portion of the said coke to raise the temperature of the remaining coke to incandescence, purifying the said gas to remove hydrogen sulphide therefrom, and returning the purified gas through the incandescent coke to remove sulphur compounds from the incandescent coke and to decompose the other sulphur compounds present in the gas.

3. The method of utilizing high sulphur coal in the production of low sulphur gas which comprises distilling the coal so as to evolve gas and produce coke, removing hydrogen sulphide from the gas thus produced, thereafter passing the gas through the coke product of distillation at an incandescent temperature to decompose other sulphur compounds in the gas, and finally removing from the gas the hydrogen sulphide resulting from the decomposition of said other sulphur compounds.

4. The method of utilizing high sulphur carbonaceous fuel in the production of low sulphur gas which comprises distilling the fuel so as to evolve gas and produce a carbonaceous residue, removing hydrogen sulphide from the gas thus produced, thereafter passing the gas through a bed of fuel at an incandescent temperature to decompose other sulphur compounds remaining in the gas, and finally removing from the gas the hy-

drogen sulphide resulting from the decomposition of said other sulphur compounds.

5. The method of utilizing solid carbonaceous fuel having a high sulphur content in making combustible gas of low sulphur content which comprises passing the fuel in a column through a shaft furnace, maintaining a high temperature zone in the lower portion of the column by intermittently blasting air therethrough, exhausting the blast gases through a heat regenerator and burning them with secondary air therein, directing water into the thus heated regenerator between blast cycles to generate steam, passing the steam so formed into the heated fuel column between blast cycles to generate gas, purifying the said gas by removal of hydrogen sulphide therefrom, returning a portion of the thus purified gas through the blast zone of the fuel column during the steam run, and again purifying the said gas to remove hydrogen sulphide therefrom.

6. The method of utilizing solid carbonaceous fuel having a high sulphur content in making combustible gas of low sulphur content which comprises passing the fuel through a shaft furnace in a column at a rate such that some unburned fuel will be discharged from the base of the column, maintaining a high temperature zone at an intermediate portion of the column by intermittently blasting air therethrough, applying water to the fuel in the lower portion of the column between periods of air blasting to quench the fuel and generate steam, passing the thus formed steam into the high temperature zone to generate gas, purifying the said gas by removal of hydrogen sulphide therefrom, returning the thus purified gas to the shaft and passing it upwardly through the fuel column together with the said steam, and again purifying the gas leaving the fuel column.

7. The method of utilizing solid carbonaceous fuel having a high sulfur content in making combustible gas of low sulfur content which comprises passing the fuel in a column through a furnace, igniting a mid-portion only of the fuel in the column, blasting air through said mid-portion to develop a high temperature therein, burning the exhaust products of said blasting operation to furnish heat for generating steam, passing the generated steam through the said fuel column to form water gas, purifying the said gas by removing hydrogen sulphide therefrom, and returning the purified gas through the said fuel column to remove undesirable constituents from the said fuel and to reduce the remaining impurities in the said gas to a form easily removed in gas purifiers.

8. The method of utilizing a solid carbonaceous fuel having high sulphur content in making low sulphur gas which comprises

- blasting air through a column of the fuel in an ignited condition to raise the temperature of a portion thereof to incandescence, thereafter passing steam through the incandescent fuel to generate water gas, removing tar and ammonia from the gas so generated, thereafter removing hydrogen sulphide from the gas, circulating the so purified gas through the incandescent fuel to remove impurities therefrom and to reduce the remaining impurities in the said gas to a form easily removed in gas purifiers, and returning the gas through purifiers to reduce its sulphur content below an allowable limit.
- 5 9. The method of utilizing high sulphur coal in the manufacture of metallurgical coke which comprises distilling gas and producing coke from the coal by passing a hot low B. t. u. gas in direct heat transferring relationship therethrough, burning a portion of the coke product of said distillation so as to raise the temperature of the remaining coke to incandescence, purifying the gas product of distillation so as to re-
- move hydrogen sulphide therefrom, and re- 25 turning a portion of the purified gas through the incandescent zone of the charge to reduce the sulphur content of the unburned coke below an allowable limit.
10. The method of utilizing high sulphur coal to produce combustible gas of low sulphur content which comprises distilling gas and producing coke from the coal by passing a hot low B. t. u. gas in direct heat transferring relationship therethrough, 30 burning a portion of the coke product of said distillation to raise the temperature of the remaining coke to incandescence, purifying the enriched gas product of said distillation by removal of hydrogen sulphide there- 35 from, and returning a portion of the thus purified gas through the incandescent zone of the charge so as to reduce the organic sulphur content of the gas below an allowable limit.
